UNITED STATES PATENT OFFICE.

LEROY J. BUTTOLPH, OF EAST ORANGE, NEW JERSEY, ASSIGNOR TO COOPER HEWITT ELECTRIC COMPANY, A CORPORATION OF NEW JERSEY.

COLOR-FADE-TESTING APPARATUS.

Application filed September 27, 1923. Serial No. 665,247.

To all whom it may concern:

Be it known that I, LEROY J. BUTTOLPH, a citizen of the United States, and resident of East Orange, county of Essex, State of New Jersey, have invented certain new and useful Improvements in Color-Fade-Testing Apparatus, of which the following is a specification.

The present invention relates to apparatus for subjecting colored articles to the influence of ultra violet light for the purpose of quickly predetermining the life of the colors under the influence of sunlight or other light or for comparing the lives of different colors. The apparatus of this invention is capable of general application in the testing of colors, dyes, paints, and so on of whatever nature and on whatever kind of material applied.

20 The object of this invention is to provide a source of light rich in ultra violet rays and in conjunction therewith means for holding dyed or colored materials such as cloth, paper, etc., or painted articles for the purpose of exposing the applied paint, color or dye to said source of ultra violet light during the process of test fading the color.

In the drawing Fig. 1 shows an elevation view of a multi-paneled holding drum mounted on a standard and a base on the latter of which is carried a casing holding apparatus auxiliary to the electric source of ultra violet light.

Figure 2 is a plan view of the holding drum.

Figure 3 is a vertical sectional view of the drum showing a fused quartz mercury vapor arc lamp mounted therein as the source of ultra violet light and also showing openings in the sides of the drum with colored fabrics exposed therethrough.

Figure 4 shows a detail of means for detachably holding sample holding frames in position across openings in the turn.

45 Figure 5 shows a mercury vapor lamp ultra violet light source mounted on one of the panels of the turn together with auxiliary apparatus therefor and means for tilting the lamp for starting an arc therein.

50 Figure 6 shows the details of means for limiting the tilting of the mercury arc lamp.

Figure 7 shows a plan view of a sample

holding frame with a sample clamped therein, and the clamping means.

Figure 8 shows a longitudinal mid-section view through the holder of Figure 7.

The fused quartz mercury vapor arc lamp, 1, which is used as a source of light rich in ultra violet rays is held to the cabinet frame member, 21, by means of bracket, 11, and the control rod, 10.

To the inner end of rod, 10, is fixed the mounting, 7, which holds the clips 5 and 6 which in turn receive the end caps of lamp 1. These end caps being of metal serve both as mounting members and as the electrical conductors between the electrodes of the lamp and the clips 5 and 6.

To the clips 5 and 6 is connected a suitable source of electric current. On the outer end of the control rod 10 is fixed the turning knob, 12, by means of

which the lamp is tilted for starting. On the rod 10 is fixedly mounted the member, 14, which engages screw, 16, which passes through bracket 11.

A notch in the member 14 receives the end of screw, 16, and the amount of rotation of rod 10 and therefore of lamp 1 can be adjustably determined by the angle of said notch and the adjustment of screw 16.

The spring 13 inserted between the cabinet frame, 21, the frame 14 serves to hold the lamp and its supporting members rigidly. Opposite frame 21 is a screw member 17 which is connected across the top by means of braces 20 and at the bottom by braces 23.

The head, 24, which is mounted on standard, 25, is fixed to said braces 23 at their mid point. These members, namely, 20, 21 and 23 form a frame on each side of which are mounted shell casings 2 to form an enclosure for the lamp 1.

Between the members 20 at their midpoints is fixed a bridging member 19 which serves to hold the baffle plate 3 which shields the light from the opening at the top of the lamp enclosure. By means of screw 17 and thumb piece 18 said baffle 3 is adjusted in its relation to the opening at the top of the enclosure to allow a circulation of air through the enclosure. Near the bottom of the enclosure is the baffle 4 which is mounted on head 24 and parts 23.

The edges of this baffle are turned upward to form a baffle pan, the baffle in this form serves to hold

water for regulating the humidity within the enclosure. Its outer edge extends beyond the opening at the lower end of the enclosure and so prevents light from passing out while at the same time it allows for the circulation of air. The shell casings 2 are formed with a plurality of plain faces or panels whereby the assembled enclosure forms a polygonal shell. In these faces or 10 panels are provided openings 26 which serve for the passage of light to articles being tested. Over these openings 26 are fixed the baffle shells 22 closed at the sides and open at their tops and bottoms. Over these openings 15 are held the sample frames 27 having grill openings in them to register with the opening 26 over which they are respectively mounted, said frames 27 being held on the baffles by means of pins 28. The samples 20 to be tested are held on the sample frames 27 by means of plates 28 which are braced against the sample and frame 27 by means of springs 29 which are fixed to frames 27. These frames with their mounted samples 25 are insertable through the top and bottom ends of baffles 22.

In the use of my apparatus I mount a sample of colored cloth, for instance between a baffle plate 27 and a plate 28 and 30 insert the sample within one end of one of the baffles 22 and keep it there exposed to light from the source 1 for the desired period of time. Any number of plates within the capacity of my apparatus can be 35 tested at once for instance a comparative test. Or between openings the enclosure can be used for exposing samples for individual or separate tests.

For comparative time test of the dye of 40 a piece of cloth I insert part of a sample piece between the holder 27 and its plate 28 exposing it only through one of the openings 30. After subjecting it to the light for a given length of time I move the piece 45 so as to register the exposed area to another of the openings 30 and to expose a new area. Then by exposing again for a given length of time I secure fading results 50 for different given lengths of time on the same piece.

The lamp casing is rotatably movable on the standard, 25, which fits into the head 24, which is fixed to the bottom of the lamp

casing frame members 23, the movement in either direction being controlled by stop 55 pin 31.

I claim as my invention:

1. In combination a source of light rich in ultra violet rays, a frame member about said light, shell members removably mounted on either side of said frame to form an enclosure for said light, openings at the top and bottom of said enclosure, an adjustable baffle plate at the top opening, a baffle plate at the bottom opening, said bottom baffle 60 having its edge turned upwardly to form a pan, openings in the walls of the shell members, baffle plates on the outside of said openings closed at the sides and open at the top and bottom, and removable sample 65 frames within the last said baffles, said sample frames having openings registering with the openings in the shell member. 70

2. In color fading apparatus, a source of light, a frame member about said light, parallel shell members removably mounted one on each side of said frame to form an enclosure about said light source, an opening at the top of said enclosure and one at the bottom thereof, an adjustable baffle across 80 said upper opening, a baffle across said bottom opening having its edges turned upwardly to form a pan, openings in said panel, light shields over said openings, and sample holding frames detachably mounted 85 between said shields and openings. 90

3. In a fading cabinet, in combination, a standard; a casing revolvably mounted on said standard, said casing comprising a vertical frame fixed to said standard, a baffle-pan fixed to said standard and within 95 said frame, an adjustable baffle fixed to said frame opposite said baffle-pan, and shell casings detachably mounted to either side of said frame, said shell casings having their sides parallel and having upper and lower rims terminating within the boundaries of said baffles; a fused quartz mercury vapor lamp mounted in said casing and supported by said frame by means permitting 100 rotation of the axis of the lamp for starting.

Signed at Hoboken in the county of Hudson and State of New Jersey this 27th day of September A. D. 1923.

LEROY J. BUTTOLPH.
